UNITED STATES PATENT OFFICE.

LOUIS ELIE FONTAINE, OF LEVIS, QUEBEC, CANADA.

ANCHOR POST AND BRACE.

1,119,943.

Specification of Letters Patent. Patented Dec. 8, 1914.

Application filed May 4, 1914. Serial No. 836,168.

To all whom it may concern:

Be it known that I, LOUIS ELIE FONTAINE, a subject of the King of Great Britain, and resident of Levis, Province of Quebec, Dominion of Canada, have invented certain new and useful Improvements in Anchor Posts and Braces, of which the following is the specification.

This invention relates to anchor posts and locking devices attached thereto, and particularly refers to a type designed to be used as surveyors' land marks, fences, anchor braces for telegraph poles, foundation bolts or posts for columns and generally on all kinds of constructional work where anchor posts are required, and the objects of the invention are to facilitate in anchoring posts or bolts in the ground, cement or the like in such a manner that they can not be extracted therefrom by an axially applied tensile stress and are only liable to be displaced by excavating, to simplify the construction and reduce the number of working parts, to render the several parts easily assembled and adapted to better perform the functions required of them and it consists essentially of the improved construction of anchor post and locking device particularly described and set forth in the following specification and accompanying drawings forming part of the same.

In the drawings, Figure 1 is a perspective view of the improved anchor post (broken in the center). Fig. 2 is a perspective view of the locking sleeve adapted to secure the anchor post in the desired position. Fig. 3 is a view of the improved device (partly broken away) used as a brace. Fig. 4 is a view of the improved device (partly broken away) used as a surveyor's land mark. Fig. 5 is a view of the improved device (partly broken away) used as a foundation post or bolt. Fig. 6 is an enlarged cross section on the line 2-2, of Fig. 1.

45 Like characters of reference refer to like parts in the several drawings.

Referring to the drawings, A represents the improved device comprising the anchor post 1 and the locking sleeve 2. This anchor post is formed with a circular stem 3, the lower end of which is formed integral with and extends from the apex of the circular cone 4 which in turn is formed integral with the downwardly disposed circular cone 5, the apex of which lies in the longitudinal axis of the said post, such conical end being

provided with a plurality of longitudinally extending grooves 6 in its outer periphery designed to form cutting edges with the said outer periphery.

The upper end 7 of the stem 3 is flattened out as shown in Figs. 1 and 4 when the anchor post 1 is designed to be used as a land mark, while it is provided with an orifice 7^a extending therethrough or a thread 8 when the said post is adapted to be utilized as a brace or a foundation bolt. This locking sleeve is designed to slidably fit the stem 3 and is provided at its lower end with a plurality of longitudinally extending arms 9 formed integral therewith, such arms being provided with beveled lower edges 10, the object of which will be made clear hereafter. When such an anchor post is to be used as a land mark or a brace as illustrated, in Figs. 4 and 3, the post 1 is driven into the ground to the desired depth. The locking sleeve is now fitted over the stem 3 and driven into the ground whereupon the arms 9 engaging with the outer periphery of the upper cone 4 are spread or splayed outwardly. To facilitate in the driving of the sleeve into the ground the bottom edges of the arms 9 are beveled which gives a cutting edge adapted to penetrate hard strata. It will be quite clear that any axial pull on the post 1 only tends to further spread the arms 9 of the sleeve 2 thereby locking the said post more firmly in the desired position.

In Fig. 3 a tension wire 11 is shown attached at one end to the orifice 7^a such wire being designed to be attached at the other end to the object it is found desirable to brace.

When this device is utilized as a foundation bolt or post as illustrated in Fig. 5, the locking sleeve 2 is fitted over the stem 3 in the desired position with the arms 9 splayed outwardly, when it is firmly embedded in concrete. The upper threaded end 8 of the stem projects above the surface of the concrete whereby columns or the like can be attached thereto by means of nuts.

It will be quite clear that an anchor post of this description once embedded in concrete is quite incapable of being loosened, and that any axial pull only tends to lock the post more securely in position. The post may be made of any suitable material but it is necessary that the sleeve should be of a resilient material such as steel or the like

which gives the necessary strength and permits of the arms 9 being suitably splayed.

As many changes could be made in the above construction and many apparently 5 widely different embodiments of my invention, within the scope of the claims, constructed without departing from the spirit or scope thereof, it is intended that all matter contained in the accompanying specification and drawings shall be interpreted as 10 illustrative and not in a limiting sense.

What I claim as my invention is:

An anchor post of the class described comprising a stem having an enlarged lower end 15 consisting of an upwardly disposed cone formed integral with a downwardly disposed cone, such cones being provided with

longitudinally extending grooves in the outer periphery, and being designed to be driven into the ground, and a sleeve adapted to 20 slidably fit said stem, such sleeve being provided with a plurality of longitudinally extending arms in its lower end having the bottom edges beveled, such arms being designed to engage with the outer periphery 25 of the said upwardly disposed cone and to be splayed outwardly thereby, substantially as described.

In witness whereof I have hereunto set my hand in the presence of two witnesses. 30

LOUIS ELIE FONTAINE.
